DESIGN FOR A SIGNAL DEVICE

Peter von Frantzius, Chicago, Ill.

Application August 2, 1947, Serial No. 140,674

Term of patent 14 years

(Cl. D72—1)

To all whom it may concern:

Be it known that I, Peter von Frantzius, a citizen of the United States, residing at Chicago, in the county of Cook and State of Illinois, have invented a new, original, and ornamental Design for a Signal Device of which the following is a specification, reference being had to the accompanying drawing, forming a part thereof.

In the drawing:

Figure 1 is a perspective view of a signal device, showing my new design;
Figure 2 is a side elevational view;
Figure 3 is a top plan view; and
Figure 4 is a bottom plan view.

I claim:

The ornamental design for a signal device, substantially as shown.

PETER VON FRANTZIUS.
